UNITED STATES PATENT OFFICE.

WLADYSLAW THEODORE KOSINSKI, OF BROOKLYN, NEW YORK.

LOCK-SEAL FOR BOTTLES.

SPECIFICATION forming part of Letters Patent No. 687,319, dated November 26, 1901.

Application filed January 3, 1901. Serial No. 41,971. (No model.)

To all whom it may concern:

Be it known that I, WLADYSLAW THEODORE KOSINSKI, a citizen of the United States, residing at Brooklyn borough, in the county of 5 Kings and State of New York, have invented certain new and useful Improvements in Lock-Seals for Bottles, of which the following is a specification.

My invention relates to a combination of a 10 seal with bottles, jars, or other receptacles for containing liquids or other substances usually held, in which the bottle must necessarily be defaced by being partially broken in order to permit the contents of the bottle to be 15 emptied or removed from, so that the emptied bottle or jar cannot again be used for containing the original liquid or filling of the bottle or jar, thereby showing the purchaser that he is obtaining the original package, so long as he 20 sees that the mouth of the bottle or jar remains unbroken, as will be hereinafter fully described and claimed.

Figure 1 is a vertical sectional view of the neck of a bottle, showing the cap or hood placed over the mouth of the bottle, its cut-out mortise with its horizontal groove in the bottom part, a bell-mouthed eye-screw and staple, the embedded barbed bifurcated spring locking-key, the tenon or raised lip 25 over the rim of the mouth of the bottle and its horizontal perforation, and the cork flush with the mouth of the bottle. Fig. 2 is a vertical view, partly in perspective, of the neck of the bottle, showing the raised tenon or lip with 30 the horizontal perforation in line with the mouth of the bottle. Fig. 3 is a horizontal view, partly in perspective, of the cap or hood placed over the mouth of the neck of the bottle, showing the cut-out mortise and the tenon 35 or raised lip and the outer rim-flange of the cap. Fig. 4 is an inside bottom plan view of the cap or hood, showing the outer rim-flange, nick, and mortise, the grooved-out bed for the barbed bifurcated spring locking-key, the 40 bell-mouthed screw-ring and staple to be embedded in and be flush with the face of the bottom of the cap or hood, and the groove for the tie-wire to rest in. Fig. 5 is a sectional horizontal view in line with the mouth of the bottle, showing the inserted barbed bifurcated 45 spring locking-key, the flanged rim-cap, and the flexible tie-wire, securing the cap around

and over the mouth of the bottle and to a stud-pin on top of the cap. Fig. 6 is a sectional horizontal view of the bottle when the 55 seal is broken, showing the inserted cork flush with the mouth of the bottle and the barbed bifurcated spring locking-key embedded, secured, and held in the cap, the tire-wire as relieved by the withdrawn pin, and by lifting the cap showing the tenon or raised lip broken. Fig. 7 represents an enlarged sectional view of the bell-mouthed screw-ring with the inserted barbed bifurcated spring locking-key, staple, and tie-wire. Fig. 8 represents a modification. Instead of the screw-ring a bell-mouthed tube is used and secured by staples. Figs. 9 and 10 represent another modification. In this device the mechanism is reversed. Instead of the barbed bifurcated 70 spring locking-key and screw-ring a solid barbed or capped locking-key is inserted into a split screw-ring or split flange-plate. Fig. 11 represents the base of an ordinary cork-bottling machine as placed over the mouth 75 of the bottle, provided with a mortise to prevent breaking the tenon while corking the bottle.

Referring to the accompanying drawings, 1 designates the neck of an ordinary bottle, 80 provided with the elevated tenon or raised lip 2, having the perforation 3 for the insertion of the barbed bifurcated or split spring locking-key 4 with its engaging barbs or catches 5 at its pointing end and the loop or eye 6 to hold the flexible tie-wire 7. The cap or hood 8 is provided with a transverse groove 9, a bell-mouthed screw-ring 10, and staple 11 on its inside face or bottom for the barbed bifurcated spring locking-key 4 to be slid and 90 housed in, the barbs or catches 5 of the bifurcated spring locking-key 4 expanding at the outer lesser orifice of the bell-mouthed screw-ring 10, preventing permanently the withdrawal of the barbed bifurcated spring locking-key 4 from its engaged housing. It is obvious that the expanded barbed bifurcated spring locking-key will compress while inserted in the groove 9, provided with the staple 11 and bell-mouthed screw-ring 10, and re-expand and engage at the outer outlet of the lesser orifice of the bell-mouthed screw-ring, 95 as shown in Figs. 1, 6, and 7. The cap or hood, with its outer flange-rim 13, the open

- mortise 12, the nick or notch 19, and the flexible tie-wire 7, firmly holds the cap when placed over and around the mouth of the bottle, the open mortise protecting and guarding the elevated tenon 2, housed in the nick formed by the open mortise, from untimely breaking, at the same time exposing to view the integral entirety of the sealed bottle as not tampered with, as shown in Figs. 1, 3, and 5.
- 10 The flexible tie-wire 7 is threaded through the loop or eye 6 and twisted downward to below the flange 14 of the reinforcement 17 at the top part of the neck of the bottle to relieve any pressure of the barbed bifurcated spring
- 15 lock-key 4 on or against the tenon or lip 2 in order to prevent untimely breaking of the tenon. Then the two ends of the flexible tie-wire are brought around each side of the bottle below the flange 14 and again twisted to
- 20 tie the surrounding loop and then brought upward and fastened around the stud-pin 16 on top of the cap 8, the cap having the nick 19 to embed the tie-wire before fastening, as shown in Figs. 4, 5, and 6.
- 25 The mortise in the cap 8 in combination with the mechanical device of the barbed bifurcated spring locking-key 4, with its housing and holding parts, as described, aids the breaking off of the tenon 2 at its perforated
- 30 weakened part when about opening the sealed bottle by raising the cap on the transverse side from the mortise. The cork stopper being flush with the mouth of the neck of the bottle prevents chips of glass from the broken
- 35 mortise, if any, from entering the bottle and with the flush embedded parts of the mechanism in the inside bottom face part of the cap and rim-flange the two surfaces make a close contact and fit.
- 40 When all the parts of this mechanical device are placed together as described, the bottle cannot be opened without detection and the breaking of the tenon 2.

Having thus fully described my invention, 45 what I claim, and desire to secure by Letters Patent, is—

1. The combination of a vessel of frangible material, as bottle or jar, having a raised perforated tenon or lip, 2, from on and over the

rim of the mouth of the bottle or jar, with a 50 bifurcated spring locking-key, 4, having expanding barbs or catches, 5, at its pointing end, the barbed bifurcated spring locking-key, 4, inserted and threaded through the perforation, 3, in the tenon, 2, and slid into 55 the horizontal groove, 9, in the inside bottom part of the mounted cap or hood, 8, and held there in place by staple, 11, and housed in and passed through the bell-mouthed screw-ring, 10, the barbs or catches expanding and 60 engaging and fastening at the outer and lesser diameter of the bell-mouthed screw-ring, as and for the purpose set forth.

2. The combination of a bottle-mouth or vessel of frangible material, having a perforated tenon or lip on and over its rim mounted by a flanged cap or hood, 8, having a mortise, 12, nick or notch, 19, to protect and house, also expose to view, the tenon, as not tampered with, combined with the groove, 9, holding the embedded, barbed, bifurcated spring lock-key, 4, screw-ring, 10, and staple, 11, substantially as specified.

3. The combination of the mouth of a vessel of frangible material, as a bottle or jar having a perforated tenon, 2, on and over its rim covered with a cap, 8, having the nick, 19, and stud-pin, threaded through the loop, 6, twisted downward and around the neck of the bottle into the flange, 14, to relieve pressure 80 from tenon, 2, embedded in nick, 19, of the cap, 8, and fastened to the stud-pin, as set forth.

4. The combination of a vessel of frangible material, as a bottle, having a raised perforated tenon, 2, from on and over the rim of the mouth of the bottle, mounted by the rim-flanged cap, 8, having the mortise, 12, and nick, 19, the stud-pin, 16, and tie-wire, 7, with the embedded barbed bifurcated spring lock-key, 4, screw-ring, 10, and staple, 11, in the groove 9.

In testimony whereof I affix my signature in presence of two witnesses.

WLADYSLAW THEODORE KOSINSKI.
